UNITED STATES PATENT OFFICE.

ANTON J. HAUG, OF NASHUA, NEW HAMPSHIRE.

APPARATUS FOR CRUSHING MATERIAL.

Application filed October 15, 1924. Serial No. 743,825.

This invention relates more especially to machines designed to be used in the paper industry to crush paper making materials and to work them into better condition for use in the paper making process.

The invention aims especially to devise a machine for reducing comparatively coarse fibrous materials, particularly wood, to a finer state without grinding or transversely cutting the fibres of such materials.

At the present time an important use for such machines is found in the paper industry in the working of the tailings rejected by pulp screens into good pulp. It is contemplated also that such machines may be used to do much of the work heretofore done by grinders. In the practical use of such machines in a mill it is frequently desirable to run materials of different sizes, kinds and qualities through a given machine and to vary the crushing action in accordance with the nature of the materials and the results desired, some materials requiring working for a longer period than others and a greater pressure being desirable under some circumstances than others. Accordingly, it is an important object of this invention to devise a machine which can be adjusted for these variations in conditions, preferably while the machine is in operation.

The nature of the invention will be better understood from the following description of a preferred embodiment of the invention, and the novel features will be more particularly pointed out in the appended claims.

In the drawings:

Figure 1 is a plan view of one form of apparatus which may be employed to embody the invention;

Fig. 2 is a longitudinal sectional elevation of the same apparatus, showing outside view of the roll and bearings for roll;

Fig. 3 is a view in elevation of the inlet end of the apparatus;

Fig. 4 is a fragmentary transverse sectional elevation taken on line A—A in Fig. 2, looking toward the inlet of the apparatus.

The construction shown in the drawings comprises a casing 1, preferably of approximately the form of a hollow cylinder although it may also be conical or of other suitable shape. The opposite ends of the cylinder are partly closed by annular shoulders 2 and

3, respectively. This casing is supported for rotative movement upon an inner roller 4 which preferably has a diameter at least half as large as the internal diameter of the casing, and it is provided with journals 5 and 6 mounted in bearings 7—7 at opposite ends of the machine, these bearings being supported on bearing stands 9 which are mounted on a base 11.

The two rotating members 1 and 4 thus are mounted in suitable relationship to crush material between them, the roller revolving on a fixed axis while the casing can yield or move somewhat with reference to it to accommodate the material being worked. Such material is subjected to the structural weight of the casing and in the construction shown means is also provided for increasing the pressure of the casing on the roller. This means comprises a chain 13 running on a chain wheel or sprocket wheel 14 which surrounds the casing at approximately the middle thereof, the wheel being bolted to a ring 15 cast on said casing. The chain also runs on a second sprocket wheel 16 located below the casing and mounted on a shaft 17 which is supported in bearing bosses 18—18 formed on the arms 19—19 of a fork shaped lever 23, the lever being fulcrumed on lugs 20—21 which are formed on the machine base 11. Weights 22 are adjustable on the lever 23 to vary the pressure with which the revolving casing 1 bears on the roller 4. In order to drive the roller 4 its journal 6 is equipped with a pulley 23* which is adapted to be driven from any suitable source of power. In many cases the rotary motion imparted to the casing by the roller 4 is sufficient for satisfactory operation. In other cases, however, it is preferable to drive the casing as well as the roller. For this purpose ring gears 32—32 are bolted to rings 33 and 34, respectively, surrounding the casing near opposite ends thereof. These gears are driven by pinions 35—35 which are secured to a horizontal shaft 37 mounted in bearings 38—38 which are supported on arms 39—39 projecting from the bearing stands 9—9 at the opposite ends of the machine frame. This shaft is equipped with a cone pulley A which is driven by a belt C from another cone pulley B that is mounted fast on the journal 5 of the roller 4, a belt shifting device D being arranged to be op-

erated by the hand wheel E to adjust the belt to produce the desired driving ratio between the roller 4 and the shaft 37.

In order to hold the casing 1 properly centered, guide rolls 43—43 are mounted loosely on the shaft 37 between the gears 36 and collars 45, and similar rolls 44 are mounted on a shaft 42 which is supported in bearings 41—41 provided in arms 40—40 which project 10 from the bearing stands 9—9. These guide rolls engage guide rings 33 and 34 fast on the casing 1 and prevent any substantial lateral movement of the casing.

The material to be crushed is fed into the 15 casing through a feed spout 48 which is fastened to one of the bearing stands 9 by means of a foot 49. This material is discharged from the machine through an outlet chute 50 which is fastened by means of a foot 51 to 20 the bearing stand 9 at the opposite end of the machine. Preferably this discharge chute 50 has one edge shaped to scrape the material from the inner surface of the casing, the chute being bent to guide this material out of the 25 casing and downwardly into any suitable receptacle.

Two stationary scraping bars 52 and 53 are mounted in the casing and preferably extend approximately through the casing, their 30 left-hand ends, Fig. 2, being pivotally connected to the outlet chute at 54 and 55, respectively, while their opposite ends are slidably mounted in slots 56 and 57, respectively, provided in webs 58—59 cast on or attached 35 to the inlet chute 48. Both bars are inclined downwardly toward the outlet end of the casing and the bar 52 scrapes material from the inner surface of the casing 1, while the bar 53 scrapes such material from the roller 40 4. These bars serve not only to remove the material from the two crushing members 1 and 4, but also act, due to their inclination, to advance the material toward the outlet of the machine, this advancing action on any 45 given unit of material occurring step by step as the material is brought into contact with one bar or the other after each crushing action. By unscrewing the bolts 60 and 61 which secure the right-hand ends of the bars 50 to the inlet spout and sliding the same in their respective slots, the inclination of the bars may be adjusted with the result that the advancing movements imparted to the stock by them will be correspondingly increased or 55 diminished.

The bar 53 is not always required for the successful operation of the machine, the necessity for its use depending upon the kind of material handled and the speed with which 60 the working parts of the machine are operated.

When the machine is in operation, the materials are fed through inlet 48 to the interior of casing 1, which is intended to be 65 driven sufficiently rapidly—whether by fric-

tional contact with positively driven roller 4 or by specially provided driving means as shown in the drawings—to develop centrifugal force, which will hold out against the casing the materials delivered upon it, the revolution of said casing obviously carrying the materials to the pinch between it and the roller upon which it is suspended. Here, where the two rolls (casing 1 and roller 4) meet in a relatively small circular angle, the 70 materials are pressed, crushed, or drawn out—not cut—and with an amount of pressure which may result entirely from the 75 constructional weight of the casing, or from any contrivance whereby said casing is weighted down or otherwise brought to bear with the desired pressure upon the sustaining roller 4.

After the materials have undergone a crushing action, they usually still adhere to the inner surface of the revolving casing, which, in the course of its revolution, next carries the materials against bar 52, which scrapes the said materials from that particular spot on the casing and advances them 80 slightly lengthwise of the same. They are again brought up to the top of the machine, 85 again subjected to a crushing action, and again scraped and advanced by the bar, the final scraping action of the bar occurring directly above the mouth of the materials-outlet 50, into which the materials eventually fall.

Should it be found that the materials discharged from the machine are excessively fine, the crushing pressure may be diminished by sliding weights 22 inwardly along lever 23 and thereby decreasing the downward pull of casing 1 against roller 4. Such adjustment will cause the materials to be subjected to gentler crushing actions, but to the same 100 number thereof as before the adjustment was made. Or, if desired, the number of crushing actions received by the materials may be lessened through the agency of the adjustable bar 52, a greater axial inclination of which 105 will hasten the passage of the materials through the machine. Where a finer ultimate product is desired, reverse adjustments to those described above are made, with corresponding results, and in some cases, both 110 the pressure of the casing upon the roller 4 and the axial inclination of the materials-advancing bar are altered with beneficial effect.

It should also be noted that machines embodying the principles of this invention are valuable for use in mixing bleach with pulp or paper stock of a relatively heavy density, 115 since it has been found that it is possible to accelerate the bleaching action by repeatedly pressing the pulp or stock charged with the bleaching liquor. The machine herein described and claimed accomplishes such repeated pressing actions in a simple, efficient manner.

While I have herein shown and described an embodiment of my invention which I prefer at present, it will be understood that the invention may be embodied in many other forms without departing from the spirit or scope thereof.

I claim:

1. A materials working machine having means to rotate the materials and separate materials-advancing means arranged in a descending longitudinal direction toward the outlet of the machine.

2. In a materials working machine, a continuous member to advance the materials from inlet to outlet of the machine, said member being inclined slightly from a parallel with the axis of the machine.

3. A materials working machine having a casing and a member at the outlet end of the casing to scrape the materials from the said casing, and to discharge the same outside the machine.

4. A materials working machine having a rotating drum, a roller within said drum and supporting the latter, and a member to remove pulp adhering to said roller.

5. A materials working machine having a rapidly revolving exterior casing, and means to alter the pressure of said casing on the materials without interrupting the operation of the machine.

6. In a materials working machine, means to subject the materials to repeated crushing actions, and means for adjusting both the number and pressure of said crushing actions without interfering with the operation of the machine.

7. A machine for working paper stock or similar material comprising a casing, a supporting member for said casing, means to rotate said supporting member, means connected to said rotating means to drive said casing and means to adjust the pressure exerted by said casing without interfering with said driving means.

8. In a machine for working paper stock or similar material employing a casing and an eccentric support for said casing, a drive for said casing, a drive for said support, means connecting said two drives whereby the former is actuated from the latter, and means to move the casing toward said support without interfering with the operation of either one of said drives.

9. In a materials working machine, the combination with a rotating casing, of an internal roller adapted to support said casing and to rotate therewith, and means to increase or diminish the pressure of said casing against said roller during the operation of both.

10. In a machine for crushing paper making materials and the like, the combination of two rotary members mounted one inside the other in position to crush material be-

tween them, and means for pressing the outer of said members toward the inner member, said means being adjustable to vary the pressure so applied.

11. In a machine for crushing paper making materials and the like, the combination of two rotary members mounted one inside the other in position to crush material between them, mechanism for supporting the inner of said members for rotation on a fixed axis, and means for pressing the outer of said members toward the inner member, said means being adjustable while said members revolve to vary the pressure so applied.

12. In a machine for crushing paper making materials and the like, the combination of two rotary crushing members mounted one inside the other, the outer member being supported on the inner member, and means for adjusting the pressure of one of said members against the other.

13. In a machine for crushing paper making materials and the like, the combination of two rotary crushing members mounted one inside the other, the outer member being supported on the inner member, and means adjustable while said members revolve to vary the pressure of one member against the other.

14. In a machine for crushing paper making materials and the like, the combination of two rotary members mounted one inside the other in position to crush material between them, and mechanism including a lever for pressing one of said members toward the other, said mechanism being adjustable to vary the pressure so applied.

15. In a machine for crushing paper making materials and the like, the combination of two rotary members mounted one inside the other in position to crush material between them, one of said members consisting of a roller mounted to rotate on a fixed axis, and the other consisting of a casing of substantially larger internal diameter than said roller and mounted to yield relatively to the roller, and means for adjusting the pressure of said casing against said roller.

16. In a machine for crushing paper making materials and the like, the combination of a roller, bearing mechanism supporting said roller for rotation, a casing in which said roller is mounted, said casing being supported on said roller for rotation in contact therewith, a chain encircling said casing and revolving therewith, and a weighting mechanism for said casing operating through said chain.

17. In a machine for crushing paper making materials and the like, the combination of a roller, bearing mechanism supporting said roller for rotation, a casing in which said roller is mounted, said casing being supported on said roller for rotation in contact therewith, a chain encircling said casing and revolving therewith, a lever, a sprocket car-

ried by said lever and over which said chain runs, said sprocket and lever being supported by said chain, and a weight mounted on said lever.

- 5 18. In a machine for crushing paper making materials and the like, the combination of two rotary members mounted one inside the other in position to crush material between them, and a continuous device extending substantially from the inlet to the outlet of the machine and operative to advance the materials being crushed step by step toward the outlet.
- 10 19. In a machine for crushing paper making materials and the like, the combination of a rotary casing, a roller mounted in said casing to support the casing and to rotate therewith, means for feeding material to be crushed into said casing, and means for advancing said materials through said casing step by step, whereby a given unit of material will be subjected to repeated crushing actions, said advancing means being adjustable to vary the number of said actions.
- 15 20. In a machine for crushing paper making materials and the like, the combination of two rotary members mounted one inside the other in position to crush material between them, one of said members consisting of a roller and the other of a casing of substantially larger internal diameter than said roller, a bar positioned in said casing lengthwise thereof and arranged to scrape the material off the inner surface of the casing, and
- 20 means for supporting said bar in a position inclined with reference to the axis of said casing.
- 25 21. In a machine for crushing paper making materials and the like, the combination of two rotary members mounted one inside the other in position to crush material between them, one of said members consisting of a roller and the other of a casing of substantially larger internal diameter than said roller, a bar positioned in said casing lengthwise thereof and arranged to scrape the material off the inner surface of the casing, and means for supporting said bar for adjustment into different positions of inclination
- 30 relatively to the axis of said casing.
- 35 22. In a machine for crushing paper making materials and the like, the combination of two rotary members mounted one inside the other in position to crush material be-

tween them, and means for scraping the material being crushed off the inner surface of said outer member and advancing said material step by step through the machine.

40 23. In a machine for crushing paper making materials and the like, the combination of two rotary members mounted one inside the other in position to crush material between them, one of said members consisting of a roller and the other of a casing of substantially larger internal diameter than said roller, and a scraper for removing the material being crushed from said roller and advancing it toward the outlet of the machine.

45 24. In a machine for crushing paper making materials and the like, the combination of two rotary members mounted one inside the other in position to crush material between them, one of said members consisting of a roller and the other of a casing of substantially larger internal diameter than said roller, and inclined scrapers positioned to act on both said roller and casing.

50 25. In a machine for crushing paper making materials and the like, the combination of a roller, bearing mechanism supporting said roller for rotation, a casing in which said roller is mounted, said casing being supported on said roller for rotation in contact therewith, means for feeding material to be crushed into one end of said casing, a discharge chute for said material at the opposite end of said casing, and a scraper for removing the material from said casing and guiding it into said chute.

55 26. In a machine for crushing paper making materials and the like, the combination of a roller, bearing mechanism supporting said roller for rotation, a casing in which said roller is mounted, said casing being supported on said roller for rotation in contact therewith, means for feeding material to be crushed into one end of said casing, a discharge chute for said material at the opposite end of said casing, and a scraper located in said casing and extending longitudinally thereof from the inlet substantially to the outlet, said scraper being inclined and arranged to direct the material being crushed toward said chute.

In testimony whereof I have signed my name to this specification.

ANTON J. HAUG.
